COLLAPSIBLE GOLF BAG STANDARD

Ivan H. Mowry, Spartanburg, S. C.

Application July 28, 1952, Serial No. 301,267

1 Claim. (Cl. 248—96)

This invention relates to a support means for a golf bag and particularly to a collapsible standard to which the bag is attached, and is automatically placed in supporting position when the bag is set down and automatically retracted into folded position when the bag is picked up.

One of the inconveniences in playing golf is that if no human caddy is used, the player must set his bag of clubs on the ground before making a shot. If he needs another club than the one he is holding for the stroke, he must stoop down, pick up the bag and rummage around until he has found the right club. This slows up the game and, at times, causes the player to lose his touch. Wheeled carriers have been used to avoid this inconvenience, but such wheeled carriers are limited in their use since they cannot conveniently be taken into the rough.

It is to avoid the above mentioned inconveniences and annoyances that the present invention has been devised. By the use of this invention, the player has his golf bag in substantially upright position at all times, and he need merely walk over and select the right club. In addition, the bag is never subject to injurious dampness from lying on the wet ground or from dust when lying on dry ground.

It is, therefore, one object of this invention to remove the petty annoyances caused by not having the instant selection of a golf club available to a player.

Another object of this invention is to provide a means for keeping a golf bag off wet, muddy or dusty ground.

Another object of this invention is to provide a golf bag support which can be easily used in any kind of terrain.

Another object of this invention is to provide a means to keep a golf bag in substantially upright position when not being carried.

Another object of this invention is to provide a golf bag support which automatically adjusts to either an extended operative position or a folded carrying position.

Another object of this invention is to provide a golf bag support which is light in weight.

Other objects of this invention are to provide an improved device of the character described, that is easily and economically produced, which is sturdy in construction, and which is highly effective in operation.

With the above and related objects in view, this invention consists in the details of construction and combination of parts, as will be more fully understood from the following description, when read in conjunction with the accompanying drawing in which:

Fig. 1 is a side elevational view of a golf bag with the support in folded position.

Fig. 2 is a view of the support in open, operative position and supporting a golf bag.

Fig. 3 is a sectional view of the upper portion of the support means showing the means for collapsing or extending the support.

Fig. 4 is a view of the lower portion of the support means.

2

Fig. 5 is a top plan view of the upper attaching means for the strap which holds the bag in position.

Fig. 6 is a top plan view of the bottom holding means for the bag.

Fig. 7 is a top plan view of the pivot ears for the legs of the support.

Fig. 8 is a top plan view of the pivot ears for the linkage connecting the legs to the main support body.

Fig. 9 is a top plan view of the means for holding the legs in their folded position.

Referring now in greater detail to the drawing wherein similar reference characters refer to similar parts, there is shown a golf bag A of standard construction which has attached to it a support member B.

The support B comprises a tube 10 of any desired material, although aluminum is preferred. The tube 10 is open at both ends. At its upper end, the tube is provided with a C-shaped member 12 which is also preferably made of aluminum or the like and which is connected to the tube by any desired means such as riveting, welding, screwing, or the like. At the other end of the tube is provided a golf bag bottom support 14. The support 14 consists of a tubular portion 16 which is adapted to fit over the tube 10, a C-shaped portion 18 integral with tubular portion 16, and a bottom support projecting foot portion 20 integral with tubular portion 16 and spaced from the portion 18. A recess 22 is formed in the projecting foot portion 20 to receive the rim or flange customarily present on the bottom of a golf bag.

A pair of ears 24 are formed on the periphery of tube 10 and to these ears are pivoted a pair of legs 26. Also pivoted to the legs 26 at points spaced from the ears 24 are a pair of links 28, one link being pivotally connected to each leg 26. At their opposite ends, the links 28 are pivoted to a pair of ears 30 which extend through a slot 32 in the tube 10 and are connected to a rod 34 which is slidably positioned in the tube 10. The rod 34 extends through the bottom of tube 10 and ends in a point 36. A stop ring 38 is mounted on the rod just above the point to prevent the rod from digging too deeply into the ground. The ring 38 is slanted relative to the rod because when the support is in bag holding position, the rod is slanted relative to the ground, and the ring is positioned so that it will be parallel with the ground. Similar rings 40 and 42 are provided on the pointed ends of the legs 26 as well. A flange 44 is provided on the rod 34 within the tube and a spring 46 is positioned between the flange 44 and the bottom wall of the tube 10 surrounding the bottom opening. This spring resiliently supports the rod in the tube. A C-shaped member 48 is attached to the tube 10 at its lower portion and is adapted to keep the legs in folded position.

The C-shaped member 12 is provided with an opening 50 at the end of each of its arms, and each of these openings is adapted to securely hold a portion of a strap 52, the strap portion being bent over the hole and sewed, clamped or otherwise secured in a loop. The strap 52 holds the upper portion of the bag in place while the lower portion of the bag rests on member 20 with the bag's flange within recess 22. The bottom portion of the bag is secured in position by a strap 54 whose portions are looped through openings 56 in the C-shaped portion 18.

In operation, when the bag is to be placed in position, it is lowered to the ground with the point 36 of the rod 34 abutting against the ground first. As the bag is pressed downwardly, the rod 34 remains stationary while the tube slides downwardly relative thereto. This moves the slot 32 downwardly relative to the ears 30, causing the links 28 to move outwardly carrying the legs out with them. The rod 34 and the legs 26 are then firmly embedded with their points in the ground and with the rings 38, 40 and

42 abutting the ground. The golf bag is then in operative standing position.

When the bag is picked up, the spring 46 automatically moves the rod downwardly, causing the links 28 to move downwardly, carrying the legs 26 with them. The legs 26 are then secured in their folded position by enclosing them within the member 48.

Although this invention has been described in considerable detail, such description is intended as being illustrative rather than limiting, since the invention may be variously embodied, and the scope of the invention is to be determined as claimed.

What is claimed as the invention is:

A readily attachable and detachable support means for golf bags or the like comprising an elongated tubular member of a length substantially equal to a golf bag, a golf bag top embracing and securing means comprising a rigid C-shaped member and flexible member thereon secured to the top end of said elongated tubular member, a golf bag bottom supporting and embracing means comprising a rigid C-shaped member and a flexible member thereon for embracing the golf bag and a recessed projecting foot for extending underneath the golf bag, a portion adapted to extend underneath the golf bag, a spring-pressed rod slidable within said elongated tubular member, a slot in said tubular member, linkage connected 25 to said rod and extending through said slot, and legs to said rod and extending through said slot, and legs pivoted at their intermediate portions to said linkage,

said legs being additionally pivoted at one end to the outer periphery of said tubular member, said rod, when pressed against the ground, adapted to cause said linkage to pivotally move the free ends of said legs from a position adjacent said tubular member to an extended position away from said tubular member, and said rod, when removed from contact with the ground, causing said linkage to return the free ends of said legs to a position adjacent said tubular member, the ground engaging ends of said rod and said legs having ground penetrating points and penetration limiting rings thereon spaced from said points.
